CLAIM

The ornamental design for a keyboard housing, as shown and described.

DESCRIPTION

FIG. 1 is a front right perspective of a keyboard housing with the cover in the open position, showing our new design;

FIG. 2 is a plan view thereof;

FIG. 3 is a right side elevation thereof;

FIG. 4 is a back elevation thereof; and

FIG. 5 is a front elevation thereof with the cover in the closed position, the top surface of the housing and cover being flat and unornamented.

FIG. 1FIG. 2

FIG. 3**FIG. 4****FIG. 5**
